UNITED STATES PATENT OFFICE.

JOHN DEMING REED, OF YORK, NEBRASKA.

ELECTRO-MAGNETIC CAR-UNCOUPLER.

SPECIFICATION forming part of Letters Patent No. 308,432, dated November 25, 1884.

Application filed January 30, 1884. (No model.)

To all whom it may concern:

Be it known that I, JOHN D. REED, of New York, in the county of York and State of Nebraska, have invented a new and Improved 5 Electro-Magnetic Car-Uncoupler, of which the following is a full, clear, and exact description.

The object of my invention is to provide a new and improved device for uncoupling cars 10 by electricity, whereby any desired car can be uncoupled by a person on the locomotive.

The invention consists in a car-uncoupling device adapted to be operated by electricity.

The invention further consists in the combination, with a car, of a pivoted shackle on the 15 draw-head, an electro-magnet for operating the shackle, conductors for conducting the electricity to the electro-magnets, contact strips on the ends of the cars for uniting the conductors of the several cars, and in numerous parts and details and combinations of the 20 same, as will be fully set forth and described hereinafter.

Reference is to be had to the accompanying 25 drawings, forming part of this specification, in which similar letters of reference indicate corresponding parts in all the figures.

Figure 1 is a plan view of the end parts of the under side of two cars provided with my 30 improved electro-magnetic car-uncoupler, the cars being shown coupled. Fig. 2 is a side view of the same, parts being shown in sections. Fig. 3 is a side view of a modified construction. Fig. 4 is a plan view of the under side of the same. Fig. 5 is a plan view 35 of the under side of a train of cars provided with my improved electro-magnetic uncoupler.

The draw-head A, held on the under side of the car, is held to slide in the direction of the 40 length of the car in suitable guides, the draw-head being pushed toward the end of the car by a buffer-spring, A'; acting on the draw-head in the usual manner. The draw-head is provided at its free end with a hook, A''. To the draw-head a laterally-projecting arm, B, is fastened, to which an electro-magnet, C, is secured. A U-shaped frame, D, is pivoted on the top and bottom surface of the draw-head to swing in the horizontal plane, the said 45 U-shaped frame or shackle D being provided with a vertical enlargement or loop, D', at its

free end, so that cars can be coupled on which the draw-heads are at different elevations above the ground. Springs E are secured to the shackle and draw-head and draw the 55 shackle toward the side edge of the draw-head. The shackle D is provided at its inner end with a rectangular arm, F, forming the armature of the electro-magnet C. If desired, the outer end of the arm F can be pivoted to a 60 short connecting-rod, G, pivoted to an armature, F', as shown in the modification on the right-hand side of Figs. 1 and 2.

Above each draw-head A a transverse bar, J, is held parallel with and a short distance 65 from the end of the car, from which bar J a series of rods, K, project toward the car and are held to slide in tubular or like casings L, projecting from the end of the car, which casings contain spiral springs L', held between 70 the ends of the casing, and a cross-piece or block, L'', on the rod, and thus serve as buffers, and at all times hold the bars J the same distance from the ends of the car.

From the bar J a series of contact strips or 75 tongues, M, project outward parallel with the longitudinal axis of the car, which tongues are provided with upright parts M', so as to insure a contact of the tongues when the cars are jolted or when the tongues are at slightly different elevations above the ground. The conducting-wires a, secured to the bottoms of the 80 car, have their ends secured to the inner ends of the tongues M. If desired, the tongues can be formed of two strips, N, placed edgewise and 85 having upright parts N' at the ends to insure contact at all times, as stated above. The strips are arranged V-shaped, one being longer than the other, so that the ends of the strips on one bar J can pass between the ends 90 of the strips N on the bar J of the other car, as shown in the lower part of Fig. 1. The tongues M and strips N are made of spring material, so that they will be pressed against each other and will always remain in contact. 95 The wires a are secured to the under side of the bottom of the car by staples or otherwise, and the said wires or conductors are insulated. Each car is provided with one more wire than there are cars in the train. For instance, a 100 car having eight wires can be coupled on any train of seven cars or less, or cars having five

wires can be coupled on a train of four cars or less, and a car having twenty-one wires can be coupled on a train of twenty cars or less, &c. Each car is provided at each end with as many contact-tongues as there are wires a plus two. For instance, a car having eight wires must have ten contact-tongues at each end. In Fig. 5 the tender and only three cars and a part of a fourth of a train of seven cars are shown. The tender O is provided with a switch-lever, P, a battery, Q, connected by a wire, b, with the pivoted end of the lever P, and with one of a series of contact-buttons, of which there are as many as there are wires a plus one. The said buttons are marked d d' d'' d''' , &c., and connected by wires g g' g'' g''' , &c., with the corresponding tongues M. The magnet C of the tender is connected to one of the tongues M by the wire l and to the contact-button d or wire a by wire h. At the front end of the car the magnet C is connected by a wire, h', with the second tongue. The other end of the magnet C is connected by a wire, l', with the corresponding tongue. At the rear ends of the cars the connections are the same as at the tenders. The first wire, a' , and the eighth wire, a^8 , are only used as return wires, the wire a being used when the battery is to the left, and the wire a^8 when the battery is to the right, of the train. The second wire, a^2 , extends from the third tongue M at the front to the second tongue at the rear. The third wire, a^3 , extends from the fourth tongue M at the front to the third tongue at the rear. The fourth wire, a^4 , extends from the sixth tongue at the front to the fourth tongue at the rear, and so on, as shown. If more or less conductors and more or less tongues are arranged on the car, the connections will be made correspondingly in the manner described above. The tongues, which are connected to the electro-magnets by wires l l', are shown in Fig. 5 to one side of the center of the car, but in practice they will be in the center to permit perfect connection being made whether the tender carrying the battery be at the front or rear end of the train. The operation is as follows: When the cars are coupled, the loops D' of the shackles D are swung over the hooks A' of the opposite draw-heads, and are held in place by the springs E. If a car is to be uncoupled, the corresponding circuit is closed to excite the corresponding magnets C, which magnets attract their armatures, and thereby swing the free ends of the shackles in the directions of the arrows x, thereby disengaging the shackles from the hooks of the draw-heads, and thus uncoupling the cars. For instance, if the third car, S', (shown in Fig. 5,) is to be uncoupled, the switch-lever P is placed on the button d' , and the electric current will then pass from the battery Q through the wire b, the lever P, the wire g' , the corresponding tongues M, the third wire, a^3 , of the first car, S', the corresponding tongues M, the second wire, a^2 , of the second car, S', the corresponding tongues M,

the wire h' at the front end of the third car, the magnet C on the front end of the third car, the wire l' on the front end of the third car, the corresponding tongues M, the wire l, 7c at the rear end of the second car, S', the magnet C at the rear end of the second car, S', the wire h, the return-wire a^8 of the second car, the corresponding tongues M, the wire a of the first car, corresponding tongues M, 75 wire g on the tender, and to the battery Q. If the tender O is at that end of the train opposite the one shown in Fig. 5, the battery will be connected to the return-wire a^8 , and the current will pass through one of the wires 80 to the magnet of the car to be uncoupled, wire l, through the corresponding tongues M, the wire l', magnet of adjoining car, wire m, to wire a^8 , and back to the battery. The cars couple automatically, and the corresponding tongues 85 M come in contact automatically.

Having thus described my invention, I claim as new and desire to secure by Letters Patent—

1. The combination, with a draw-head, of a swinging coupling frame or shackle, and of 90 an electro-magnet adapted to act on the said shackle, substantially as herein shown and described.

2. The combination, with a car, of electric conductors held on the same, electro-magnets 95 connected with the conductors, car-uncoupling devices adapted to be acted on by the electro-magnets, and of contact-tongues held on the ends of the cars, substantially as herein shown and described.

3. The combination, with a car, of electric conductors held on the same, electro-magnets connected with the conductors, car-uncoupling devices adapted to be acted on by the magnets, a bar held on each end of the car 105 and contact-tongues projecting from the said bars, which tongues are connected with the conductors, substantially as herein shown and described.

4. The combination, with a car, of a series 110 of contact-tongues held on the end of the same, conductors held on the under side of the car and connecting the contact-tongues on the opposite ends of the car, electro-magnets C, the wires h l and h' l', connecting the conductors 115 with the magnets C, and of a car-uncoupling device adapted to be operated by the magnets, substantially as herein shown and described.

5. The combination, with a car, of a series 120 of contact-tongues held on the end of the same, conductors held on the under side of the car and connecting the contact-tongues on the opposite ends of the car, electro-magnets C, the wires h l and h' l', connecting the magnets with the conductors, and of the wires m and n, substantially as herein shown and described.

6. The combination, with a draw-head, of 130 an electro-magnet held on an arm of the same, and of a car-uncoupling device adapted to be operated by the said magnet, substantially as herein shown and described.

7. The combination, with a draw-head, of

the electro-magnet C, held on an arm of the same, and the shackle D, pivoted on the draw-head, and provided with an arm, F, substantially as herein shown and described.

5. 8. The combination, with a car, of an electric car-uncoupling device, a bar held on the end of the car by rods projecting from the said bar into casings on the end of the car, and of contact strips or tongues projecting from the said bar, substantially as herein shown and described.

9. The combination, with a car, of an electric car-uncoupling device, a bar, J, held across the end of the car, contact strips or 15 tongues projecting from the said bar, the casings L, projecting from the end of the car, the rods K, projecting from the bar J into the casings L, and of the springs L', surrounding

the rods K and acting on the same, substantially as herein shown and described. 20

10. The combination, with a draw-head, of the coupling-shackle D, pivoted on the same, and having an arm, F, the electro-magnet C, and of the spring E, secured to the shackle and to the draw-head, substantially as herein 25 shown and described.

11. The combination, with a car, of a coupling device, an electro-magnet for operating the said device, and of conductors for conducting electricity to the said magnets, substantially 30 as herein shown and described.
